ATTORNEYS.

UNITED STATES PATENT OFFICE.

DAVID WALKER, OF NEWARK, NEW JERSEY.

DESIGN FOR A STAIR-CARPET BUTTON.

SPECIFICATION forming part of Design No. 26,960, dated April 20, 1897.

Application filed March 13, 1897. Serial No. 627,431. Term of patent 7 years.

To all whom it may concern:

Be it known that I, DAVID WALKER, a citizen of the United States, residing at Newark, in the county of Essex and State of New Jersey, have invented and produced a new and original Design for a Stair-Carpet Button; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 In the drawings, Figure 1 is a front elevation of my newly-designed stair-carpet button; and Fig. 2 is a section of the same, taken on line *x*.

20 The leading feature of my design consists of a stair-carpet button triangular in front elevation.

In said drawings, *a* indicates the button, *b* the central perforation, and *c* long radial ornaments extending from a rounded ornament *d* outward into the angles *eee*. Between the 25 radial ornaments *c* are shorter radial ornaments *f*, which extend toward the sides of the button. These several radial ornaments are rounded at their outward extremities, and at the edges the button is ornamented by marginal beads *g*, extending substantially parallel with the sides.

What I claim as new is—

The design for a stair-carpet button herein shown and described. 35

In testimony that I claim the foregoing I have hereunto set my hand this 16th day of January, 1897.

DAVID WALKER.
